UNITED STATES PATENT OFFICE.

HARVEY GILES, OF BROOKLYN, NEW YORK, ASSIGNOR TO ARTEMAS WARD, OF NEW YORK, N. Y.

DESIGN FOR A COIN-OPERATED VENDING-MACHINE CASING.

49,333.

Specification for Design.

Patented July 11, 1916.

Application filed April 29, 1916. Serial No. 94,502. Term of patent 3½ years.

To all whom it may concern:

Be it known that I, HARVEY GILES, a citizen of the United States, residing at Brooklyn, in the county of Kings and State of New York, have invented a new, original, and ornamental Design for a Coin-Controlled Vending-Machine Casing, of which the following is a specification, reference being had to the accompanying drawings, forming a part thereof, and in which—

Figure 1 is a perspective view taken from

the left hand front corner, and Fig. 2 a corresponding view taken from the right hand front corner of a coin-controlled vending machine embodying my design.

I claim:

The ornamental design for a coin-controlled vending machine casing, as shown.

HARVEY GILES.
